(57) **CLAIM**

The ornamental design for a vibration compactor, as shown and described.

DESCRIPTION

FIG. 1 is a left front perspective view of a vibration compactor according to the present design;

FIG. 2 is a left side view thereof;

FIG. 3 is a right side view thereof;

FIG. 4 is a front plan view thereof;

FIG. 5 is a rear plan view thereof;

FIG. 6 is a bottom plan view thereof;

FIG. 7 is a top plan view thereof;

FIG. 8 is a right front perspective view thereof;

FIG. 9 is a right rear perspective view thereof; and,

FIG. 10 is a left rear perspective view thereof.

The subject matter shown in dashed lines are for illustrative purposes only and forms no part of the claimed design.
